UNITED STATES PATENT OFFICE

110,767

DESIGN FOR A CORDUROY FABRIC

Jack Leventhal, Laurelton, Long Island, N. Y., assignor to Crompton Company, West Warwick, R. I., a corporation of Rhode Island

Application March 2, 1938, Serial No. 75,527

Term of patent 3½ years

To all whom it may concern:

Be it known that Jack Leventhal, a citizen of the United States, residing at Laurelton, Long Island, in the county of Queens and State of New York, has invented a certain new, original, and ornamental Design for Corduroy Fabrics, of which the following is a specification, reference being made to the accompanying drawing, forming a part thereof.

The drawing is a plan view of a corduroy fabric showing my new design.

I claim:

The ornamental design for a corduroy fabric, substantially as shown.

JACK LEVENTHAL.
